UNITED STATES PATENT OFFICE.

EDMUND S. CHURCH, OF DAYTON, OHIO, ASSIGNOR, BY MESNE ASSIGNMENTS, TO
GEORGIANA L. CHURCH, OF CHICAGO, ILLINOIS.

INTERNAL-COMBUSTION ENGINE.

1,133,007.

Specification of Letters Patent. Patented Mar. 23, 1915.

Application filed August 24, 1910. Serial No. 578,801.

To all whom it may concern:

Be it known that I, EDMUND S. CHURCH, a resident of Dayton, in the county of Montgomery and State of Ohio, have invented 5 certain new and useful Improvements in Internal-Combustion Engines, of which the following is a full, clear, and exact description.

The invention relates to engines of the 10 type in which a combustible or explosive agent, such as air and hydrocarbon is supplied to a cylinder of the engine and ignited to operate one of the engine elements relatively to the other.

15 In the operation of reciprocating explosive engines of the four cycle type, it is now common practice to draw a charge of combustible mixture into the cylinder during the out-stroke of the piston and to compress 20 that charge during the succeeding in-stroke of the piston, to render the charge explosive or combustible, and in operation, the compression of the charge by the piston in the cylinder is substantially the same at all 25 times, since the piston-stroke is the same at all times. Resultantly, there is no substantial variation in the compression of the charge and therefore, no variation in efficiency or power, except such as results from 30 variation of the mixture admitted to the cylinder.

One object of the invention is to provide an improved internal combustion engine, in which the fluid admitted to the cylinder is 35 compressed and in which the degree of compression or density of the fluid may be readily varied so that efficiency of the engine will vary, according to the load imposed upon it.

40 The invention also designs to provide for automatic regulation of the compression or density of the charge by the load imposed upon the engine, so that the density of the charge will be increased as the load increases.

45 A still further object of the invention is to provide an automatically operating connection between the engine-shaft and the element to be driven thereby, which controls 50 the speed of the driven-element, according to the load imposed upon it, and so that if the power of the engine is insufficient to drive the driven element at a given relative speed, the driven element will be differentially op-

erated at a lower speed instead of causing 55 stoppage of the engine as frequently occurs in the operation of engines in motor-vehicles.

The invention also provides a reservoir for storing a supply of air, for delivery into the 60 cylinder in starting or for emergencies when excessive power is desired, and in which the maximum pressure of the fluid supplied to the cylinder, will be automatically retained.

A still further object of the invention is to 65 provide improved means for controlling the operation of an internal combustion engine by variation of the density of the charge introduced into the cylinder.

Another object of the invention is to provide 70 an improved pneumatic connection between the engine-shaft and the driven-shaft which causes the latter to be started gradually by the engine and which avoids the necessity of providing a friction clutch for 75 that purpose.

The invention also designs to provide an improved internal combustion engine of improved operation, control and construction.

The invention consists in the several novel 80 features hereinafter set forth and more particularly defined by claims at the conclusion hereof.

In the drawings: Figure 1 is a plan of an 85 internal combustion engine embodying the invention, the same being shown as applied to drive a motor-vehicle. Fig. 2 is a side elevation. Fig. 3 is a vertical section taken on line 3—3 of Fig. 2. Fig. 4 is a horizontal section taken at the axis of the crank-shaft. 90 Fig. 5 is a detail of the pump-connection between the engine shaft and the driven shaft. Fig. 6 is a central longitudinal section of the same. Fig. 7 is a vertical section on an enlarged scale through the air reservoir 95 and the valve mechanism for controlling the air in said reservoir. Fig. 8 is a detail section of the inspirator for the liquid fuel. Fig. 9 is a diagrammatic view of the ignition apparatus.

100 The engine illustrated in the drawings is shown as comprising four cylinders *a* although it is to be understood that the invention may be applied to engines having but one cylinder or any desired number. These 105 cylinders are mounted upon an inclosing crank-case *b*, in which a crank-shaft *c* of usual construction, is journaled. These

cranks are connected respectively to pistons *d* which operate in the cylinders, by means of pitmen *e*, in manner well understood in the art. This engine is of the four-cycle type and the upper end *a'* of each cylinder serves as an ignition-chamber and is provided with an admission-valve *f*, which controls the supply of combustible mixture to the cylinder. An exhaust-valve *g* is mounted in the admission-valve and controls the exhaust from the upper end of the cylinders. Above its admission-valve, each cylinder is provided with a port or chamber *f'* which is in communication with a manifold *f''* to which the combustible agent is conducted by an in-take pipe *f''*. Each admission-valve is normally held closed by a spring *f''* and is opened by a valve-operating mechanism comprising a lever *f''*, rod *f''* and a cam *f''* on a valve-shaft *f''* which is geared to the engine-shaft *c* in manner well understood in the art, being usually driven at the ratio of one to two with respect to the engine-shaft. Each exhaust-valve *g* is normally held closed by a spring *g'* and is operated to permit the products of combustion to escape by similar valve-operating mechanism to that employed for the admission-valves. Since, however, the particular construction of this valve-
mechanism may be similar to that now commonly employed in the art for internal combustion engines of the four-cycle type, further illustration and description is deemed unnecessary. Exhaust-port *g''* communicates with its associated valve *g* and conducts the products of combustion to a manifold *g''*, which is usually connected by a pipe *g''* to an exhaust-pipe *g''*. To provide for more effective scavenging of the cylinders, an auxiliary exhaust-pipe *g''* is connected to each cylinder and to a common exhaust-pipe *g''* which is connected to the muffler *g''*.

The engine-shaft *c* has rigidly secured thereto, a pump-carrier *h*, which serves as a momentum or fly-wheel and carries a series of pump-cylinders *h'* in each of which a piston *h''* is slidably mounted. Each of these pistons is connected to a crank or eccentric-connections. Each piston *h''* is provided with a check-valve *h''* for admitting air to the piston-chamber *h''* during every in-stroke of the piston. Port *h''* formed in the carrier *h* conducts the compressed air from the piston-chamber *h''* to an annular channel *h''* on the periphery of the hub *h''* of the pump-carrier *h*. This hub is provided with packing-rings *h''* fitting in a suitable bearing *b'* on the crank-case *b*, to form an air-tight connection between the revolving hub and said bearing. A check-valve *h''* is interposed in each port *h''* to prevent back-flow

of these pump-connections. For example, when the engine is applied to a motor-vehicle and it is desired to start the vehicle, at which time greater power is necessary of the air into the piston-chambers *h''*. The in-take pipe *f''* which is connected to the admission-manifold *f''*, is connected to the channel *h''* to receive compressed air from the pump-cylinders *h'*.

In transit to the admission-manifold, the air current takes up hydro-carbon which is delivered into the pipe, by means of a needle-valve *j* which receives liquid hydro-carbon from a supply-pipe *p'*. This valve directs the hydro-carbon in regulated quantity to a small funnel-shaped pipe *j''* in the in-take pipe *f''*. Pipe *p'* receives the liquid fluid from a reservoir *p''* and if desired, the liquid in said reservoir may be placed under pressure, corresponding to that in the in-take pipe by a pipe *p''*, which may be connected to pipe *k'* in which the pressure is the same as in the in-take pipe. The compressed air passing through in-take pipe *f''* mixes with the hydro-carbon and forms a combustible mixture which will explode when ignited in the ignition-chambers of the cylinders.

Each cylinder is provided with a spark-plug *s* of usual construction and which may be operated in any manner well understood in the art, to successively ignite the charges in the cylinders *a*.

The present invention designs to avoid the necessity of compressing the explosive agent by the pistons in the engine-cylinder and to introduce the combustible agent under compression, into the cylinder. For this purpose, the introduction of the charge is timed to occur just before the piston reaches the end of its out-stroke, so that when it reaches the limit of its stroke, the previously densified combustible agent will be in the cylinder in readiness to receive the spark for the power-stroke of the piston. The degree of compression or density of the combustible agent, is varied automatically according to the load to be driven by the engine. These results are accomplished by the pump-connections between the engine-shaft *c* and the driven-shaft *i'*, because the operation of the engine-shaft will not cause the driven-shaft *i'* to be rotated until the pressure in the in-take pipe *f''* is sufficient to retard the operation of the pump-pistons *h''* in the cylinders *h'* and to cause the pitmen *h''* to drive the crank *i* on the driven-shaft. Resultantly, when the engine is running, the pump-carrier *h* and cylinders *h'* will rotate and cause the piston *h''* to slide therein, as a result of the movement of the pistons relatively to the wrist-pin *i''* on crank *i*, so that these pumps will operate to force air into the in-take pipe *f''* until the pressure therein is sufficient to retard or prevent the movement

of the pistons h^2 in their cylinders h' , then the driven-shaft i' will be operated by means than when the vehicle is under headway, the engine will operate without driving the shaft i' until the necessary pressure has been developed in the in-take pipe to retard the movement of the pistons h^2 in their cylinders h' and therefore, by reason of this increased compression in the in-take pipe, the efficiency or power of the motor will be increased to start the car according to the resistance or load imposed upon the shaft i' . Pressure in the in-take pipe will be automatically maintained, to re-place the volume supplied to the engine cylinders by reason of the differential travel of the shaft i' relatively to the engine-shaft c , which occurs whenever the pressure in the in-take pipe is reduced below that required to drive the load or to prevent movement of the pump pistons h^2 in their cylinders i .

To provide initial pressure to start the engine or auxiliary pressure, in event that is desirable in emergencies, a reservoir k is provided and is connected by a pipe k' to the channel h' in the hub of the pump-carrier so that air from the pumps will also be forced through pipe k' into the reservoir k , where sufficient pressure will always be maintained to start the engine. A check-valve k^2 is included in the pipe k' to prevent back-flow of the air from the reservoir. This check-valve may be manually opened by a connection comprising a rod k^3 , gears k^4 , k^5 , shaft k^6 , gears k^7 , k^8 and a hand-wheel k^9 mounted on the dash board 10 of the vehicle. Resultantly, when auxiliary pressure is desired at any time to increase the efficiency of the engine, without waiting for the pumps to develop the necessary pressure in the in-take pipe, the operator may open valve k^2 to cause the pressure in the in-take pipe, which is in communication with the reservoir by means of pipe k' and channels h' , to be raised to the pressure in the reservoir k . The pressure in the reservoir may be indicated to the operator by a gage 11 connected to the pipe k' by a pipe 12. A blow-off pipe 13 is also connected to the pipe k' . A shut-off cock 14 is provided so that when the engine is not in operation, the pressure in the reservoir may be retained therein. The maximum pressure developed in the operation of the pumps will also be attained in this reservoir, and after the reduction of pressure, it will be automatically raised to the maximum by the operation of the pumps.

The supply of combustible mixture to the in-take manifold, is controlled by a throttle-valve l so that the speed of the engine may be controlled in that manner. A connection comprising a lever l' , rod l^2 , bell-crank lever l^3 , which may be mounted on the post in which the steering-shaft is journaled, a rod l^4 and an arm l^5 secured to said valve, places

this throttle-valve under the control of the operator, so that the speed of the engine may be readily controlled and varied at will.

In order to manually control and vary the relative speed of the driven-shaft k' and the engine-shaft c , by permitting pistons h^2 to operate differentially in their cylinders h' , a device is provided for controlling the pressure in the in-take pipe f^3 and whereby the pressure in the pipe may be reduced. By permitting escape of the air from the in-take pipe, the differential travel of the engine, relatively to the shaft i' , will vary. This device consists of a valve m mounted in a branch f^{15} of the in-take pipe f^3 . A check-valve f^{16} closes communication between the in-take pipe f^3 and branch f^{15} , and a spring f^{17} has sufficient force to prevent any escape of air until pressure in the in-take pipe is greater than the minimum required for operating the engine, for example, 15 pounds. The operator can manipulate the controller-valve m by a connection comprising an arm m' secured to said valve, a link m^2 , and an arm m^3 on the lower end of a shaft m^4 having a handle m^5 at its upper end. By turning handle m^5 , the controller-valve m may be opened more or less to reduce the pressure in the in-take pipe, and by permitting the air therein to escape, the operator may vary the speed of travel of the driven-shaft i' . The driven-shaft i' may be connected to operate the driving wheels n of the vehicle by means of suitable shafts and gearing now common in the art.

An automatically operating switch o is provided for keeping the electric-circuit in which the spark-plugs are included, open, until the minimum pressure for operation of the engine has been developed in the in-take pipe. A piston o' is slideable in a branch o^2 of the in-take pipe and is operated inwardly by a spring o^3 , which is of sufficient force to hold the plunger inwardly until the pressure in the in-take pipe is sufficient for an explosive mixture. Piston o' is connected to a stem o^4 which is adapted to engage a contact-terminal o^5 which is included in the circuit for the spark-plugs s , as diagrammatically shown in Fig. 9. In starting the engine, when there is no pressure in the in-take pipe, the sparking-circuit will be interrupted at switch o until sufficient pressure has been developed in the pipe to produce an explosive-mixture and then the pressure in the pipe will be sufficient to close the circuit at this switch and cause the spark-plugs to become operative. Thus, this device serves as means for automatically rendering the ignition-system inoperative until the necessary pressure for operation of the engine by the combustible mixture has been developed.

The operation of the mechanism set forth will be as follows: Assuming that there is

no pressure in reservoir k and it is desired to start the engine, the engine may be turned manually by a crank q which is adapted to be connected to the engine-shaft c in usual manner. Rotation of the engine-shaft will cause pump-carrier h to rotate therewith, while the eccentric pin i^2 on the resistance or driven-shaft will remain stationary and such rotation will cause the piston h^2 to be operated back and forth in their pump-cylinders h' . Such operation of the pistons will cause air to pass into the chambers h^5 through check-valves h^4 and to be forced through ports h^6 , through channel h^7 , and in-take pipe f^3 , into manifold f^2 and supply ducts f' . When the pressure in the in-take and supply-pipes reaches the minimum necessary for ignition, say 15 pounds, plunger v' will be forced outwardly and close the ignition circuit at switch o , and thereupon the ignition-apparatus will become operative to ignite the charges successively forced into the chambers a' of the cylinders, under control of the in-take valves f . In transit through the in-take pipe f^3 , the air will carry with it the hydro-carbon supplied to the in-take pipe through needle-valve p . The combustible charge will be admitted to each cylinder just before the piston reaches the end of its last cycle, and as soon as it reaches the limit of that in-stroke, the charge will be ignited for the power-stroke of the piston. As the piston reaches the end of its power-stroke, the products of combustion will escape from auxiliary exhaust-pipe g^8 , and during the next cycle, exhaust-valve g will be open to permit the products of combustion to escape, through valve g^2 and the manifold g^3 . If desired this exhaust-valve may be permitted to remain open until a portion of the last cycle, so that the cylinder will be thoroughly scavenged before the next ignition occurs. The engine having been started, the pressure in the in-take pipe will be maintained by the operation of the pumps. When the pressure in the in-take pipe has been raised sufficiently to cause the movement of the pump-pistons h^2 to be retarded, the pitmen h^3 will become operative to drive crank i and shaft i' and air to displace the volume supplied to the cylinders will be provided by the working of the pump-pistons h^2 in the cylinders h' whenever the pressure in the in-take pipe decreases. If it is desired to run the engine free until the operator desires to drive the vehicle or shaft i' , sufficient air may be permitted to escape by the manipulation of throttle valve l , to reduce the pressure in the in-take, so that the resistance of shaft i' and its load will exceed that necessary to retard longitudinal travel of pistons h^2 in cylinders h' . During operation of the engine, the reservoir k will also be filled and

the pressure will be maintained therein equal to the maximum pressure developed in the in-take pipe. Check-valve k^2 will keep the pressure in the reservoir until the operator desires to use this pressure, in which event it may be controlled by hand-wheel k^9 to supply air, under pressure, to the cylinders either in starting or to increase the efficiency of the engine when it is running. The speed of the engine may also be controlled by throttle valve l .

In driving the vehicle, the controller-valve m may, at any time, be used to permit some of the air in the in-take pipe to escape and in this manner the relative speed of the vehicle and the engine may be varied, as well as controlled, without the necessity of manipulating a friction-clutch or gearing for that purpose.

The mechanism thus set forth exemplifies an engine in which the density of combustible-agent consumed in the engine-cylinders, may be varied at will, to vary the efficiency or power of the engine; it also exemplifies mechanism by which the density of the combustible agent will be varied automatically according to the load imposed upon the engine and will be automatically controlled by the load, so that when a heavy load or resistance (for example, in starting the vehicle) opposes the movement of the driven-shaft i' , the pump-connections will become operative to increase the pressure in the in-take pipe and the degree of compression or density of the combustible-agent and correspondingly vary the relative speed of the driven-shaft and engine, thus effecting an increase of power and a reduction of speed when desired or necessary in moving the load. The pump-connections associated with the controller-valve for regulating the pressure in the in-take pipe, also exemplifies mechanism by which the degree of compression of the combustible agent may be manually varied to cause differential operation of the driven-shaft relatively to the engine-shaft without the use of a friction-clutch or other gearing, and this mechanism may also serve as a throw-off or connection which permits the engine to be operated independently of the driven shaft or element.

The invention is not to be understood as restricted to the details shown and described, since these may be modified within the scope of the appended claims without departing from the spirit and scope of the invention.

Having thus described the invention, what I claim as new and desire to secure by Letters Patent, is:

1. The combination with an internal combustion engine, of compression-means comprising two elements, one of said elements being operatively connected to be driven by

the engine, means for conducting fluid compressed by said means to the engine, and means connecting the other element to the load to be driven, to control the compressing operation of the compression-means by the resistance of the load.

2. The combination with an internal combustion engine, of compression-means comprising two elements, one of said elements being operatively connected to be constantly driven by the engine, means for conducting fluid compressed by said compression means to the engine, means connecting the other of said elements to the load to be driven, to vary the compression of air by the compression-means, and the density of the fuel supplied to the engine correspondingly to the resistance of the load, and means for independently varying the density of the fluid supplied to the engine.

3. The combination with an internal combustion engine, of compression-means comprising two elements, one of said elements being operatively connected to be constantly driven by the engine, means for conducting fluid compressed by said elements to the engine, and means connecting the other of said elements to the load to be driven, to vary the compression operation of the compression-means, and the density of the fluid supplied to the engine correspondingly to the resistance of the load.

4. The combination with an internal combustion engine, of compression means comprising two elements, one of said elements being operatively connected to be constantly driven by the engine, means for conducting air compressed by said elements to the engine, means connecting the other of said elements to the load to be driven to vary the compression of air by the compression-means and the density of the fluid supplied to the engine correspondingly to the resistance of the load, and means for independently varying the density of the fluid supplied to the engine.

5. The combination with an internal combustion engine, of compression-means comprising two elements, one of said elements being operatively connected to be constantly driven by the engine, means for conducting air compressed by said elements to the engine, means for supplying fuel to the compressed air in transit to the engine, means connecting the other of said elements to the load to be driven, to vary the compression of air by the compression-means, and the density of the fluid supplied to the engine, correspondingly to the resistance of the load, and means for independently controlling the density of the fluid supplied to the engine.

6. The combination with an internal combustion engine, of compression-means comprising two elements, one of said elements

being operatively connected to be constantly driven by the engine, means for conducting air compressed by said elements to the engine, means for supplying fuel to the compressed air in transit to the engine, and means connecting the other of said elements to the load to be driven, to vary the compression of air by the compression-means, and the density of the fuel supplied to the engine, correspondingly to the resistance of the load.

7. The combination with an internal combustion engine, of compression-means, comprising two elements one of which is slidable in the other, one of said elements being operatively connected to be constantly driven by the engine, means for conducting fluid compressed by said elements to the engine, and means connecting the other of said elements to the load to be driven and whereby the movement of said elements to compress air will be controlled by the load and will vary the density of the fuel supplied to the engine.

8. The combination with an internal combustion engine, of compression-means comprising two elements one of which is slidable in the other, one of said elements being operatively connected to be constantly driven by the engine, means for conducting fluid compressed by said means to the engine, means connecting the other of said elements to the load to be driven, to control the operation of the compression-means by the load, and means for independently varying the density of the fluid supplied to the engine.

9. The combination with an internal combustion engine, of compression-means comprising two elements one of which is slidable in the other, one of said elements being operatively connected to be constantly driven by the engine, means for conducting fluid compressed by said means to the engine, means connecting the other of said elements to the load to be driven, whereby the operation of the compression means for compressing air, and the density of the fuel, supplied to the engine, will be varied correspondingly to the resistance of the load, and manually operable means for independently controlling the density of the fluid supplied to the engine.

10. The combination with an internal combustion engine, of compression-means comprising two elements one of which is slidable in the other, one of said elements being operatively connected to be constantly driven by the engine, means for conducting fluid compressed by said elements to the engine, means connecting the other of said element to the load to be driven, and whereby the operation of the compression-means for compressing air, and the density of the fuel supplied to the engine will be varied corre-

spondingly to the resistance of the load, and means for reducing the density of the fluid supplied to the engine.

11. The combination with an internal combustion engine, of compression-means comprising two elements one of which is slideable in the other, one of said elements being operatively connected to be constantly driven by the engine, means for conducting fluid compressed by said elements to the engine-cylinder, means for supplying fuel to the fluid compressed by said elements, and means connecting the other of said elements to the load to be driven and whereby the compression of air by said elements will be controlled by the resistance of the load.

12. The combination with an internal combustion engine, of compression-means comprising two elements one of which is slideable in the other, one of said elements being operatively connected to be constantly driven by the engine, means for conducting air compressed by said compression-means to the engine, means for supplying fuel to the air compressed by said elements, means connecting the other of said elements to the load to be driven and whereby the operation of the compression-means for compressing air, and the density of the fuel supplied to the engine, will be varied correspondingly to the resistance of the load, and independent means for controlling the density of the fluid supplied to the engine.

13. The combination with an internal combustion engine, of compression-means comprising two rotatable elements, one of said elements being operatively connected to be constantly driven by the engine, means for conducting fluid compressed by said means to the engine, and compression-means connecting the other of said elements to the load to be driven and whereby the operation of the compression-means relative to the engine will be controlled by the load to vary the density of the fluid supplied to the engine.

14. The combination with an internal combustion engine, of compression-means comprising two rotatable elements, one of said elements being operatively connected to be constantly driven by the engine, means for conducting fluid compressed by said compression-means to the engine, means connecting the other of said elements to the load to be driven and whereby the compression of fluid by said elements, will be controlled to vary the density of the fuel supplied to the engine correspondingly to the resistance of the load, and means for independently varying the density of the fluid applied to the engine.

15. The combination with an internal combustion engine, of compression-means comprising two rotatable elements, one of said elements being operatively connected to be

driven by the engine, means for conducting fluid compressed by said elements to the engine, means connecting the other of said elements to the load to be driven and whereby the compression of fluid by said elements will be controlled, to vary the density of the fuel supplied to the engine correspondingly to the resistance of the load, and manually operable means for varying the density of the fluid supplied to the engine.

16. The combination with an internal combustion engine of compression-means comprising two rotatable elements, one of said elements being operatively connected to be driven by the engine, means for conducting fluid compressed by said compression means to the engine, means connecting the other of said elements to the load to be driven and whereby the compression of fluid will be controlled, to vary the density of the fuel supplied to the engine correspondingly to the resistance of the load, and means for reducing the density of the fluid supplied to the engine.

17. The combination with an internal combustion engine, of compression-means comprising two rotatable elements, one of said elements being operatively connected to be constantly driven by the engine, means for conducting air compressed by said elements to the engine, means for supplying fuel to the compressed air in transit to the engine, and means connecting the other of said elements to the load to be driven and whereby the compression of air by said compression means will be controlled, to vary the density of the fuel supplied to the engine correspondingly to the resistance of the load.

18. The combination with an internal combustion engine, of compression-means comprising two rotatable elements, one of said elements being operatively connected to be driven by the engine, means for conducting air compressed by said elements to the engine, means for supplying fuel to compressed air in transit to the engine, means connecting the other of said elements to the load to be driven and whereby the compression of air will be controlled, to vary the density of the fuel supply to the engine correspondingly to the resistance of the load, and means independent of the load, for varying the density of the fluid supplied to the engine.

19. The combination with an internal combustion engine, of compression-means comprising two rotatable elements one of which is slideable in the other, one of said elements being operatively connected to be constantly driven by the engine, means for conducting fluid compressed by said means to the engine, and means connecting the other of said elements to the load to be driven and whereby the relative movement of said elements will be controlled, to vary

the density of the fluid supplied to the engine.

20. The combination with an internal combustion engine, of compression-means comprising two rotatable elements, one of which is slidable relatively to the other one of said elements being operatively connected to be constantly driven by the engine, means for conducting fluid compressed by said elements to the engine, and means connecting the other of said elements to the load to be driven and whereby the relative movement of said elements will be controlled by the resistance of the load.

21. The combination with an internal combustion engine, of compression-means comprising two rotatable elements one of which is slidable relatively to the other, one of said elements being operatively connected to be constantly driven by the engine, means for conducting fluid compressed by said elements to the engine, means connecting the other of said elements to the load to be driven and whereby the operation of one of said elements relatively to the other will be controlled by the resistance of the load, and means for independently varying the density of the fluid supplied to the engine.

22. The combination with an internal combustion engine, of compression-means comprising two rotatable elements one of which is slidable relatively to the other, one of said elements being operatively connected to be constantly driven by the engine, means for conducting fluid compressed by said compression-means to the engine, means connecting the other of said elements to the load to be driven and whereby the compression of air will be controlled, to vary the density of the fuel supplied to the engine, according to the resistance of the load, and manually operable means for independently controlling the density of the fluid supplied to the engine.

23. The combination with an internal combustion engine, of compression-means comprising two rotatable elements one of which is slidable relatively to the other, one of said elements being operatively connected to be constantly driven by the engine, means for conducting air compressed by said elements to the engine, means connecting the other of said elements to the load to be driven and whereby the compression of air will be controlled to vary the density of the fuel supplied to the engine, according to the resistance of the load, and means for permitting the compressed air to escape to reduce the density of the fluid supplied to the engine.

24. The combination with an internal combustion engine, of compression-means comprising two rotatable elements one of which is slidable relatively to the other, one of said elements being operatively connected to be constantly driven by the engine, means for

conducting air compressed by said elements to the engine, means connecting the other of said elements to the load to be driven, and whereby the compression of air will be controlled by the resistance of the load, and means for supplying fuel to the compressed air in transit to the engine.

25. The combination with an internal combustion engine, of a compressor, means for supplying air directly from the compressors to the engine cylinder, means for supplying combustible fluid to the air in transit to the engine, and means automatically controlled by the load upon the engine to vary the operation of the compressor according to the load imposed upon the engine.

26. The combination with an internal combustion engine, of a compressor, means for supplying air directly from the compressors to the engine cylinder, means for supplying combustible fluid to the air in transit to the engine, means automatically controlled by the load upon the engine to vary the operation of the compressor according to the load imposed upon the engine, and means for independently controlling the density of the air supplied to the engine.

27. The combination with an internal combustion engine, of a plurality of pumps, each comprising two coöperating elements, one of the elements of each pump being operatively connected to, and constantly driven by, the engine, means for connecting the other element of each of the pumps to the load to be driven by the engine, whereby the compressive action of the pumps will be varied and controlled by the load, and means for conducting fluid compressed by the pumps to the engine-cylinder.

28. The combination with an internal combustion engine, of a plurality of pumps, each comprising two coöperating elements, one of the elements of each pump being operatively connected to, and constantly driven by the engine, means connecting the other element of each of the pumps to the load to be driven by the engine, whereby the compressive action of the pumps will be varied and controlled by the load, means for conducting fluid compressed by the pumps to the engine-cylinder, and means independent of the load, for varying the density of the fluid supplied to the engine.

29. The combination with an internal combustion engine, of a plurality of pumps, each comprising two coöperating elements, one of the elements of each pump being operatively connected to, and constantly driven by the engine, means for connecting the other element of each of the pumps to the load to be driven by the engine, whereby the compressive action of the pumps will be varied and controlled by the load, means for conducting fluid compressed by

the pumps to the engine-cylinder, and manually operable means for varying the density of the fluid supplied to the engine.

30. The combination with an internal 5 combustion engine, of a plurality of pumps, each comprising two coöperating elements, one of the elements of each pump being operatively connected to, and constantly driven by the engine, means connecting the 10 other element of each of the pumps to the load to be driven by the engine, whereby the compressive action of the pumps will be varied and controlled by the load, means for conducting air compressed by the 15 pumps to the engine cylinder, and means for permitting the compressed air to escape to reduce the density of the fluid supplied to the cylinder.

31. The combination with an internal 20 combustion engine, of a plurality of pumps, each comprising two coöperating elements, one of the elements of each pump being operatively connected to, and constantly driven by the engine, means connecting the 25 other element of each of the pumps to the load to be driven by the engine, whereby the compressive action of the pumps will be varied and controlled by the load, means for conducting air compressed by the 30 pumps to the engine-cylinder and means for supplying fuel to the compressed air in transit to the engine.

32. The combination with an internal combustion engine, of a plurality of pumps, 35 each comprising two coöperating elements, one of the elements of each pump being operatively connected to, and constantly driven by the engine, means connecting the other element of each of the pumps to the 40 load to be driven by the engine, whereby the compressive action of the pumps will be varied and controlled by the load, and means for conducting fluid compressed by the pumps to the engine cylinder, means for 45 supplying fuel to the compressed air passing to the engine, and means for permitting air to escape, to reduce the density of the air passing to the engine.

33. The combination with an internal 50 combustion engine, of a plurality of rotary pumps, each comprising two coöperating elements, one of the elements of each pump being operatively connected to, and constantly driven by the engine, means connecting the 55 other element of each of the pumps to the load to be driven by the engine, whereby the compressive action of the pumps will be varied and controlled by the load, and means for conducting air 60 compressed by the pumps to the engine cylinder.

34. The combination with an internal combustion engine, of a plurality of rotary pumps, each comprising two coöperating

elements, one of the elements of each pump 65 being operatively connected to, and constantly driven by the engine, means connecting the other element of each of the pumps to the load to be driven by the engine, whereby the compressive action of the 70 pumps will be varied and controlled by the load, means for conducting air compressed by the pumps to the engine-cylinders, and means independent of the pumps, for varying the density of the fluid supplied to the 75 engine.

35. The combination with an internal combustion engine, of a plurality of rotary pumps, each comprising two coöperating elements, one of the elements of each pump 80 being operatively connected to, and constantly driven by the engine, means connecting the other element of each of the pumps to the load to be driven by the engine, whereby the compressive action of the 85 pumps will be varied and controlled by the load, means for conducting air compressed by the pumps to the engine cylinders, and means for permitting air to escape from the conducting-means to reduce the density of 90 the fluid supplied to the engine.

36. The combination with an internal combustion engine, of a plurality of rotary pumps, each comprising two coöperating elements, one of the elements of each pump 95 being operatively connected to, and constantly driven by the engine, means connecting the other element of each of the pumps to the load to be driven by the engine, whereby the compressive action of the pumps will 100 be varied and controlled by the load, means for conducting fluid compressed by the pumps to the engine cylinders, and manually controlled means for varying the density of the fluid supplied to the engine. 105

37. The combination with an internal combustion engine, of a plurality of rotary pumps, each comprising two coöperating elements, one of the elements of each pump being operatively connected to, and constantly driven by the engine, means connecting the other element of each of the pumps to the load to be driven by the engine, whereby the compressive action of the pumps will be varied and controlled by the 110 load, means for conducting air compressed by the pumps to the engine cylinders, and means for supplying fuel to the compressed air in transit to the engine. 115

38. The combination with an internal 120 combustion engine, of a plurality of rotary pumps, each comprising two coöperating elements, one of the elements of each pump being operatively connected to, and constantly driven by the engine, means connecting the other element of each of the pumps to the load to be driven by the engine, whereby the compressive action of the 125

- 5 pumps will be varied and controlled by the load, means for conducting fluid compressed by the pumps to the engine cylinders, means for supplying fuel to the compressed air in transit to the engine, and means independent of the pumps, for varying the density of air in the conducting means.
- 10 39. The combination with an internal combustion engine, of a pump, comprising a piston and a cylinder, means for conducting fluid compressed by the pump to the engine-cylinder, the pump-cylinder being operatively connected to the engine, and means connecting the pump-piston to the load to be driven, whereby the compression of fluid by the pump will be controlled and varied by the load.
- 15 40. The combination with an internal combustion engine, of a pump comprising a piston and a cylinder, means for conducting fluid compressed by the pump to the engine-cylinder, the pump-cylinder being operatively connected to the engine, means connecting the pump-piston to the load to be driven, whereby the operation of the pump relative to the engine will be controlled by the load, and means independent of the load, for varying the density of fluid supplied to the engine.
- 20 41. The combination with an internal combustion engine, of a pump, comprising a piston and a cylinder, means for conducting air compressed by the pumps to the engine-cylinder, the pump-cylinder being operatively connected to and driven by the engine, means connecting the pump-piston to the load to be driven whereby the operation of the pump relative to the engine will be controlled by the load, and manually operable means for controlling the density of the fluid supplied to the engine.
- 25 42. The combination with an internal combustion engine, of a pump comprising a piston and a cylinder, means for conducting air compressed by the pump to the engine-cylinder, the pump-cylinder being drivably connected to the engine, means connecting the pump-piston to the load to be driven, whereby the operation of the pump relative to the engine will be controlled by the load, and manually operable means for permitting compressed air to escape, to reduce the density of the fluid supplied to the engine.
- 30 43. The combination with an internal combustion engine, of a pump comprising a piston and a cylinder, means for conducting air compressed by the pump to the engine-cylinder, the pump-cylinder being drivably connected to the engine, means connecting the pump-piston to the load to be driven, whereby the operation of the pump relative to the engine, will be controlled by the load, and means for supplying fuel to the compressed air passing to the engine.
- 35 44. The combination with an internal combustion engine, of a pump, comprising a piston and a cylinder, means for conducting air compressed by the pump to the engine cylinder, the pump-cylinder being operatively connected to the engine, means connecting the pump-piston to the load to be driven, whereby the operation of the pump relative to the engine, will be controlled and varied by the load, means for supplying fuel to the compressed air from the pump, and means for permitting air to escape, to reduce the density of the fluid supplied to the engine.
- 40 45. The combination with an internal combustion engine, of a plurality of rotary pumps, each comprising a cylinder and a piston, the cylinders being connected to and constantly rotated by the engine, means connecting the pistons and the load to be driven, and means for conducting fluid under pressure from said pumps to the engine, the load acting to resist the movement of the pistons in the cylinders.
- 45 46. The combination with an internal combustion engine, of a plurality of rotary pumps, each comprising a cylinder and a piston, the cylinders being connected to and rotated by the engine, means connecting the pistons and the load to be driven, means for conducting fluid under pressure from said pumps to the engine, the load acting to resist the movement of the pistons in the cylinders, and means for supplying fuel to the air compressed by said pumps.
- 50 47. The combination with an internal combustion engine, of a plurality of rotary pumps, each comprising a cylinder and a piston, the cylinders being connected to and rotated by the engine, means connecting the pistons and the load to be driven, means for conducting fluid under pressure from said pumps to the engine, the load acting to resist the movement of the pistons in the cylinders, means for supplying fuel to the air compressed by said pumps, and means for varying the supply of fuel.
- 55 48. The combination with an internal combustion engine, of a plurality of rotary pumps, each comprising a cylinder and a piston, the cylinders being connected to and rotated by the engine, means connecting the pistons and the load to be driven, means for conducting fluid under pressure from said pumps to the engine, the load acting to resist the movement of the pistons in the cylinders, means for supplying fuel to the air compressed by said pumps and means independent of the load for varying the density of the fluid supplied to the engine.
- 60 49. The combination with an internal combustion engine, of a plurality of rotary pumps, each comprising a cylinder and a

5 piston, the cylinders being connected to and rotated by the engine, means connecting the pistons and the load to be driven, means for conducting fluid under pressure from said pumps to the engine, the load acting to resist the movement of the pistons in the cylinders, means for supplying fuel to the air compressed by said pumps, and manually operable means for varying the 10 density of the fluid supplied to the engine.

15 50. The combination with an internal combustion engine, of a plurality of rotary pumps, each comprising a cylinder and a piston, the cylinders being connected to and rotated by the engine, means connecting the pistons and the load to be driven, means for conducting air under pressure from said pumps to the engine, the load acting to resist the movement of the pistons in the 20 cylinders, means for supplying fuel to the air compressed by the pumps, means for varying the supply of fuel, and means for permitting air compressed by the pumps to escape, to reduce the density of the fluid 25 supplied to the engine.

30 51. The combination with an internal combustion engine, of means for compressing air driven by the engine, said compression means forming a driving connection between the engine and the load, the operation of which will automatically vary with respect to the engine and thereby vary the density of the air compressed by the compression means, means for conducting 35 compressed air from said compression means to the engine-cylinder, and means for supplying fuel to the compressed air.

40 52. The combination with an internal combustion engine, of means for compressing air driven by the engine, said compression-means forming a driving connection between the engine and the load which will vary automatically to operate differentially with respect to the engine and thereby automatically vary the density of the air compressed by the compression-means, means for conducting compressed air from said compression-means to the engine-cylinder, means for supplying fuel to the compressed 45 air, and independent means for varying the density of fuel supplied to the engine.

50 53. The combination with an internal combustion engine, of means for compressing air driven by the engine, said compression means forming a driving connection between the engine and the load which will operate differentially with respect to the engine and thereby vary the density of the air compressed by the compression means, 55 means for conducting compressed air from said compression means to the engine cylinder, means for supplying fuel to the compressed air, and manually operable means for varying the density of fluid supplied 60 to the engine.

65

54. The combination with an internal combustion engine, of means for compressing air driven by the engine, said compression means forming a driving-connection between the engine and the load, the operation 70 of which will automatically vary with respect to the load imposed upon the engine and thereby vary the density of the air compressed by said compression means, means for conducting compressed air from said compression means to the engine cylinder, means for supplying fuel to the compressed air, and means for reducing the density of the compressed air supplied to the engine. 75

80 55. The combination with an internal combustion-engine, of an air pump operated by the engine, said pump forming a driving-connection between the engine and the load, the operation of which will vary according to the load imposed upon the engine and thereby vary the density of air compressed by the pump, means for conducting air from the pump to the engine cylinder, and means for supplying fuel to the 85 compressed air.

90 56. The combination with an internal combustion engine, of an air pump operated by the engine, said pump forming a connection between the engine and the load, the operation of which will vary according to the load imposed upon the engine and thereby vary the density of air compressed by the pump, means for conducting air from the pump to the engine cylinder, means for supplying fuel to the compressed air, and independent means for varying the density of fluid supplied to the engine. 95

100 57. The combination with an internal combustion engine, of an air pump operated by the engine, said pump forming a connection between the engine and the load, the operation of which will vary according to the load imposed upon the engine and thereby vary the density of air compressed by the pump, means for conducting air from the pump to the engine cylinder, means for supplying fuel to the compressed air and manually operable means for varying the density of fluid supplied to the engine. 110

115 58. The combination with an internal combustion engine, of an air pump operated by the engine, said pump forming a connection between the engine and the load, the operation of which will vary according to the load imposed upon the engine and thereby vary the density of air compressed by the pump, means for conducting air from the pump to the engine cylinder, means for supplying fuel to the compressed air, and means for reducing the density of compressed air supplied to the engine. 120

125 59. The combination with an internal combustion engine, of a compressor comprising two coöperating elements, one of 130

- which is movable relatively to the other, means connecting one of the elements to the engine so it will be driven by the engine, means for conducting air from the compressor to the engine-cylinder, means connecting the other element to the load to be driven, which causes the compressed fluid between the elements of the compressor to drive the load, and means for supplying fuel to the compressed air in transit to the engine.
60. The combination with an internal combustion engine, of a compressor comprising two coöperating elements, one of which is movable relatively to the other, means connecting one of the elements to the engine so it will be driven by the engine, means for conducting air from the compressor to the engine-cylinder, means connecting the other element to the load to be driven, which causes the compressed fluid between the elements of the compressor to drive the load, means for supplying fuel to the compressed air in transit to the engine, and means for varying the density of the fluid supplied to the engine.
61. The combination with an internal combustion engine, of a compressor comprising two coöperating elements, one of which is movable relatively to the other, means connecting one of the elements to the engine so it will be driven by the engine, means for conducting air from the compressor to the engine cylinder, means connecting the other element to the load to be driven, which causes the compressed fluid between the elements of the compressor to drive the load, and means for supplying fuel to the compressed air in transit to the engine, and manually operable means for varying the density of the fluid supplied to the engine.
62. The combination with an internal combustion engine, of a rotary-pump comprising two coöperating elements, one of which is movable relatively to the other, means connecting one of the elements to the engine so it will be driven by the engine, means for conducting fluid from the pump to the engine-cylinder, means connecting the other element to the load to be driven, which causes the compressed fluid in the pump to drive the load, and means for supplying fuel to the compressed fluid in transit to the engine.
63. The combination with an internal combustion engine, of a rotary-pump comprising two coöperating elements, one of which is movable relatively to the other, means connecting one of the elements to the engine so it will be driven by the engine, means for conducting fluid from the pump to the engine-cylinder, means connecting the other element to the load to be driven, which causes the compressed fluid in the pump to drive the load, means for supplying fuel to the compressed fluid in transit to the engine.
64. The combination with an internal combustion engine, of a plurality of pumps forming a driving connection between the engine and the load, the operation of which will be varied automatically by and according to the load imposed upon the engine, and means for conducting fluid from the pumps to the engine-cylinder.
65. The combination of an internal combustion engine, a rotary pump, and means for conducting fluid from the pump to the engine cylinder, said pump forming a driving connection between the engine and the load, the operation of which will be varied automatically by and according to the load imposed upon the engine and thereby vary the density of fluid supplied to the engine.
66. The combination with an internal combustion engine, of a plurality of pumps operated by the engine, said pumps forming a driving connection between the engine and the load, the operation of which will be varied automatically by and according to the load imposed upon the engine, means for conducting air under pressure from said pumps to the engine cylinder, a reservoir connected to said conducting means to receive excess air therefrom, means for supplying the fuel to said conducting means, a check-valve for retaining pressure in the reservoir, and means for manually operating the check-valve to supply air from the reservoir to the engine.
67. The combination with an internal combustion engine, of a plurality of pumps operated by the engine, said pumps forming a connection between the engine and the load, the operation of the pumps will be varied automatically by and according to the load imposed upon the engine, means for conducting air under pressure from said pump to the engine cylinders, a reservoir connected to said conducting means to receive excess air therefrom, means for supplying the fuel to said conducting means, a check-valve for retaining pressure in the reservoir, and means for manually operating the check-valve to supply air from the reservoir to the engine, and means for reducing the pressure in said conducting means.
68. The combination with an internal combustion engine comprising a cylinder, of a pump operated by the engine, means controlled by the load on the engine for controlling the operation of the pump to compress fluid under pressure from the pump to the engine-cylinder, and means for rendering the controlling means inoperative, except when the pressure in the supply means is sufficient for the operation of the engine.

69. The combination with an internal combustion engine comprising a cylinder, of a pump operated by the engine and controlled by the load thereon, means for supplying fluid under pressure from the pump to the engine-cylinder, means for manually controlling the pressure in the supply-means, and a valve for rendering the controlling-means inoperative, except when the pressure in the supply-means is sufficient 5 for the operation of the engine.

70. The combination with an internal combustion engine comprising a cylinder, of a pump, means controlled by the load for supplying fluid under pressure from the pump to the engine-cylinder, a valve for manually controlling the pressure in the supply-means, and means for rendering said controlling valve inoperative, except when 15 the pressure in the supply-means is sufficient 20 for the operation of the engine.

71. The combination with an internal combustion engine comprising a cylinder, of a pump, means controlled by the load for supplying fluid under pressure from the pump to the engine-cylinder, a valve for manually controlling the pressure in the supply-means, and a valve for rendering said controlling-valve inoperative, except when 25 the pressure in the supply-means is sufficient 30 for the operation of the engine.

72. The combination with an internal combustion engine comprising a cylinder, of a pump operated by the engine and automatically controlled by the load thereon, means for supplying fluid under pressure from the pump to the engine-cylinder, and means for rendering the controlling-means inoperative, except when the pressure in the supply-means is sufficient for the operation 35 of the engine.

73. The combination with an internal combustion engine comprising a cylinder, of a pump operated by the engine and automatically controlled by the load thereon, means for supplying fluid under pressure from the pump to the engine-cylinder, means for manually controlling the pressure in the supply-means, and a valve for rendering the controlling-means inoperative, except when the pressure in the supply-means is sufficient for the operation of the engine.

74. The combination with an internal combustion engine comprising a cylinder, of a pump controlled by the load, means for supplying fluid under pressure from the pump to the engine-cylinder, a valve for manually controlling the pressure in the supply-means, and means for rendering said controlling valve inoperative, except when the pressure in the supply-means is sufficient for the operation of the engine.

75. The combination with an internal combustion engine comprising a cylinder, a

pump controlled by the load, means for supplying fluid under pressure from the pump to the engine-cylinder, a valve for manually controlling the pressure in the supply-means, and a valve for rendering said controlling-valve inoperative, except when the pressure in the supply-means is sufficient for the operation of the engine.

76. The combination with an internal combustion engine comprising a cylinder, of a pump operated by the engine and controlled by the load thereon, means for supplying fluid under pressure from the pump to the engine-cylinder, ignition means, and means for rendering the ignition means inoperative until the pressure of fluid supplied to the cylinder is sufficient for the operation of the engine.

77. The combination with an internal combustion engine comprising a cylinder, of a pump operated by the engine and controlled by the load thereon, means for supplying fluid under pressure from the pump to the engine-cylinder, ignition means, and means for rendering the ignition means inoperative until the pressure of the fluid supplied to the cylinder is sufficient for the operation of the engine.

78. The combination with an internal combustion engine, of a plurality of rotary pumps driven by the engine, forming a variable driving connection between the engine and the load, said pumps being connected so that their operation will be varied automatically by and according to the load imposed upon the engine.

79. The combination with an internal combustion engine, of a plurality of rotary pumps driven by the engine, forming a driving connection between the engine and the load, said pumps being connected so that their operation will be varied automatically by and according to the load imposed upon the engine, and means for conducting fluid from the pumps to the engine cylinders.

80. In an internal combustion motor, engine cylinders, coöperating engine pistons, means for the combustion of charges of air and fuel periodically in the engine cylinders, a driving element driven by the engine pistons, a driven element, a compressor driven by rotation of the driving element with respect to the driven element, and means for distributing the air compressed by the compressor to the engine cylinders, and means for throttling the delivery from the compressor to the engine cylinders.

81. In an internal combustion motor, an internal combustion engine, a driving element driven by the internal combustion engine, a driven element, a compressor driven by rotation of the driving element with respect to the driven element, means for distributing air from the compressor to the engine cylinders periodically and means for

releasing the air from the compressor to the atmosphere.

82. An internal combustion engine, an engine-cylinder, a coöperating piston, means for the combustion charges of air and fuel periodically in the engine cylinder, a driving element driven by the engine, a driven element, a compressor driven by relative rotation of the driving and the driven element, 10 means for passing air compressed by the compressor into the engine cylinder, and means for controlling the passage of air from the compressor to the engine cylinder.

83. An internal combustion engine, combustion cylinders, coöperating pistons,

means for the combustion of charges of air and fuel periodically in the combustion cylinders, a driving element, a driven element, a compressor driven by rotation of the driving element relative to the driven element, 20 means for distributing air compressed by the compressor to the combustion cylinder periodically, and means preventing return flow from the combustion cylinders to the compressor.
